(57) **CLAIM**

The ornamental design for the mudsill anchor, as shown and described.

DESCRIPTION

FIG. 1 is a perspective view of the mudsill anchor showing my design.

FIG. 2 is top plan view of the mudsill anchor of FIG. 1.

FIG. 3 is a right side elevation view of the mudsill anchor of FIG. 1.

FIG. 4 is a left side elevation view of the mudsill anchor of FIG. 1.

FIG. 5 is a bottom plan view of the mudsill anchor of FIG. 1.

FIG. 6 is a lower end elevation view of the mudsill anchor of FIG. 1.

FIG. 7 is a perspective view of an alternate embodiment of the mudsill anchor showing my design.

FIG. 8 is top plan view of the mudsill anchor of FIG. 7.

FIG. 9 is a right side elevation view of the mudsill anchor of FIG. 7.

FIG. 10 is a left side elevation view of the mudsill anchor of FIG. 7.

FIG. 11 is a bottom plan view of the mudsill anchor of FIG. 7; and,

FIG. 12 is a lower end elevation view of the mudsill anchor of FIG. 7.
